UNITED STATES PATENT OFFICE.

JASPER N. HOWARD, OF WICHITA, KANSAS.

SAW-FILING MACHINE.

SPECIFICATION forming part of Letters Patent No. 527,332, dated October 9, 1894.

Application filed February 18, 1894. Serial No. 500,099. (No model.)

To all whom it may concern:

Be it known that I, JASPER N. HOWARD, a citizen of the United States of America, residing at Wichita, in the county of Sedgwick and State of Kansas, have invented certain new and useful Improvements in Saw-Filing Machines, of which the following is a specification, reference being had therein to the accompanying drawings, and figures of reference thereon, forming a part of this specification, in which—

Figure 1. is a perspective view of my improved saw filing machine. Fig. 2. is an end view of the same. Fig. 3. is a cross-sectional view of the sliding guide head. Fig. 4. is a sectional top view of the same. Figs. 5 to 10. inclusive are detail views of the same. Fig. 11. is a cross-sectional view of the vertically adjusting thumb-screw in connection with 20 the thimble with the spring inclosed. Fig. 12. is a bottom plan of the same with the spring omitted. Fig. 13. is a cross-sectional view of the thimble and spring. Fig. 14. is a side view of a rod provided with lugs for operating and locking the saw-clamp. Fig. 15. is a perspective view of the saw-clamp.

This invention relates to certain improvements in saw filing machines, having an adjustable sliding head for holding the file in 30 any desired position, also in the construction of the saw-clamp.

Referring to the drawings 1 represents a frame secured to a table or bench 34 by means of the clamp 32 and set-screw 33. The frame 35 1 is provided with rods, 2, which pass through the holes 13, in the sliding guide head, which is adapted to slide laterally. The lower portion of the head 6 is movable vertically and rotary. It is movable vertically by means of 40 the standard 17 passing through the hole 38 in the cylinder 9, and is held in position by the thumb-screw 3, and the spring 8, and it is adjustable rotary, through the medium of the cylinder 9, which is held in place by the 45 set screw, 10, and the groove 11.

The guide-block 7 is pivoted at 36 to the legs 40, and is held in the desired position by the set-screw 35. It is also provided with the hole 37, through which the file guide rail 18 50 passes freely, backward and forward. Said file guide rail is provided at one end with a fixed depending arm 19, while the opposite

end has a like depending arm movably secured to the rail by means of the set-screw 23. The file handles 21 pass through the depending arms 19 as shown at 20 and are adapted to be rotated to set the file 22 at any degree of angle, when they are securely held in place by the set-screw 41.

The saw-clamp is pivoted at either end, at 24 to the frame 1, and is provided with the cross rail 39 secured at either end to the clamp jaws 29, the saw 42 is placed between the clamp jaws 29 and the cross-rail 30 of the frame, the clamp is tightened against the saw by means 65 of the cross-rod 28, which is provided with the handle 27 and the lugs 31, the rod is adapted to turn in the frame 1, the lugs are turned upward and forward into the notches 26 of the arm 25 of the saw-clamp, thus raising the arm 70 25 which in turn draws the arms 29, and cross rail 39 snugly against the saw, which is held on the other side by the cross rail 30 of the frame 1.

The sliding guide head is provided with two 75 gages 15 and 16 for marking the angle at which the file is set, the gage 15 is composed of a segment of a circle on one side of the lower part of the sliding guide head 6 (see Figs. 2, 3, 4, 5, and 6,) and rotates in conjunction with 80 the lower guide head 6, and its pointer 14 projects out on the same side of the upper part of the guide-head 5. (See Figs. 2, 3, and 4.)

The gage 16 is on the segment of the guide-block 7 and the edge of the leg 40 indicates 85 the angle of the guide rail 18.

In use the frame is secured to the bench by the clamp 32 and the set-screw 33, the saw is then placed in the saw clamp, and the file adjusted as follows: The thumb-screw 3 is ad- 90 justed so as to allow the file to go down the desired distance, thus making the saw tooth of a certain length, then the thumb-screw 10 is loosened and the cylinder is turned to de- 95 sired angle, so that the file can cut the saw tooth at a certain bevel, which would be indicated by the gage 15, then the set-screw 10 is turned snugly into the groove 11 of the cylinder 9, and for still further adjusting the file and guide bar, the set-screw 35 is loosened 100 and the guide block 7 is set at the desired angle, designated by the gage 16, when the set-screw is tightened against the guide block 7. When the file is set at the desired angles, the

sliding head is slid to either end of the frame, on the rods 2, when by pressing down on the handles 21, the spring 8 will yield and allow the file to come in contact with the saw-tooth, then the file is worked back and forth until the head of the set-screw 3 rests upon the top of the guide head 5, which will prevent the file from cutting the saw tooth any deeper, then the pressure on the handles 21 is released and the spring 8 lifts the file and frame from the saw, the guide head is slid to the next tooth and the work is repeated.

Having thus described my invention, what I claim as new and useful, and desire to secure 15 by Letters Patent, is as follows:

1. In combination with a saw-clamp, the frame 1, the rods 2, the sliding guide head, provided with the set screws 3, spring 8, cylinder 9, the vertically adjustable guide head 20 6, the guide block 7, with a file guide rail 18, all arranged and operated, as shown and described.

2. In a saw-filing machine, the combination of a supporting frame 1, the sliding guide head 5, and 6, adjustable vertically, and rotary, said head held to slide upon the rods 2, the guide block 7, the transverse guide rail 25 18, adapted to slide in said guide block 7, the

rotary adjustable file handles 21 the gage in conjunction with the guide head, and the saw 30 clamp pivotally secured to said frame 1, substantially as shown, and for the purpose specified.

3. In a saw-filing machine, in combination with the frame 1, and cross rods 2, the sliding 35 guide head, made in two sections 5 and 6, the thumbscrew 3, spring 8, cylinder 9, set screw 10, the perpendicular adjustable stand 17, guide block 7, gage 15, and the file guide rail 18, adapted to slide in said guide block 7, 40 all arranged and operated as shown and described.

4. In combination with a saw filing machine, the saw clamp, pivoted to the frame 1, the depending jaws 29 connected at their lower extremity by the cross rail 39, the cross rod 28, pivotally secured to the two standards of the frame 1, said cross rod provided at one end with the handle 27; and lugs 31, the jaws 25, provided with the notches 26, all arranged 45 and operated substantially as shown, and specified.

JASPER N. HOWARD.
